United States Patent Office

Des. 228,367
Patented Sept. 11, 1973

228,367

FONT OF ELECTRO-OPTICAL CHARACTERS

Brian Astle, Hightstown, N.J., assignor to Optel
Corporation, Princeton, N.J.

Filed Feb. 17, 1972, Ser. No. 227,335

Term of patent 14 years

Int. Cl. D18—04

U.S. Cl. D64—12 B

The figure on the drawing is a face view of a font of electro-optical characters illustrating my new design and showing the basic character together with the numerals formed therefrom as well as another embodiment for the numeral zero.

I claim:

The ornamental design for a font of electro-optical characters, as shown and described.
